UNITED STATES PATENT OFFICE.

BERNHARD S. F. ELL, OF ENGELHOLM, SWEDEN.

BRAIDING-MACHINE.

1,075,342.

Specification of Letters Patent. Patented Oct. 14, 1913.

Application filed June 18, 1910. Serial No. 567,231.

To all whom it may concern:

Be it known that I, BERNHARD S. F. ELL, a subject of the King of Sweden, residing at Engelholm, Sweden, have invented a new and useful Braiding-Machine, of which the following is a specification.

This invention relates to a braiding machine for forming or weaving a covering on wire or the like.

10 The principal objects of the invention are to provide an improved machine for this purpose which, without any increase in size will operate on a much larger amount of thread, and at greater speed and which will 15 do better work. These results are accomplished in part by having two rows of spools for holding the thread rotating concentrically in opposite directions about the wire to be covered, one of the rows preferably being 20 above a plate or disk and the other below it, and carrying the threads from the lower spools up between the upper spools and reciprocating the threads radially in order to cause the upper spools to pass between the 25 successive lower threads alternately so as to form the braided tubular fabric. In one form the upper spools slide on a circular guide and are pushed and pulled forward by a series of rotary shafts movable around 30 in a circle. Thus all the parts rotate except the pipes for carrying and reciprocating the threads of the lower spools, which are carried back and forth by a rotating 35 crank. The slack in the threads of the lower spools is taken up by spring tension, this dispensing with the ordinary weights and avoiding the speed limitations imposed by such weights.

The invention also involves numerous features of construction and modes of operation which will be referred to hereinafter.

Reference is to be had to the accompanying drawings in which—

Figure 1 is a side elevation of a machine 45 constructed in accordance with this invention; Fig. 2 is a plan of the machine. Figs. 3 and 4 are similar plans on enlarged scale showing the parts in two other positions. Fig. 5 is a central section. Fig. 6 is an 50 elevation of one of the stands for the top spools. Fig. 7 is transverse section of the same. Fig. 8 is a central section of another form in which the invention can be embodied. Fig. 9 is a plan of the same with 55 parts removed. Figs. 10 and 11 are plans of the same showing the parts in different

positions, and Fig. 12 is a section on the line 12—12 of Fig. 9.

In the form shown in the first seven figures the machine comprises a frame 10 having a central vertical hollow guide or pipe through which the wire *a* to be covered passes from a reel below and is wound over a reel 12 above. This reel is operated in well-known manner by means of a worm 60 and worm wheel connection 13 driven from a shaft 14 and driving the reel through gearing. Power is applied through a clutch pulley 16, or the like, located on a driving shaft 17 which is journaled on the frame 65 70 and is provided with a bevel gear 18. This gear meshes with two bevel gears 19 and 20 on opposite sides, one of which is fixed to a vertical hollow shaft 21, and the other to a hollow hub 22 rotatable outside the 75 shaft 21. The hub 22 is provided with a circular disk 23 projecting from it and rotating with it. Projecting down from this disk are a plurality of spindles or spool 80 holders 24 spaced equally and concentrically around the disk and each carrying a spool or bobbin 25 for the lower threads *b*. The thread *b* passes from each of these lower spools through a guide 26 and from there through a thread carrier 27. In passing to 85 the thread carrier 27 the thread passes under a spring 30 constituting a tension device and through an eye in a spring-pressed member 31 located on the guide 26. It then passes through a perforation 32. The member 31 is normally pressed upwardly by the spring, but is held down by the thread under tension, but when the thread breaks the spring projects the member up into a 90 position to engage an arm 33 on a rod 34, as 95 the disk rotates. This lifts a stop-piece 35 from engagement with a hook on the shipling lever 36 and permits a spring 37 to throw this lever out and disengage the movable member of the clutch from the pulley 100 16. Thus the machine is stopped whenever a thread breaks.

Equally spaced around the center of the disk 23 are a series of vertical shafts 40 mounted in bearings on the disk. On each 105 of these shafts is an arm 41 connected by a link 42 with one of the thread carriers 27. As the disk rotates these shafts are rotated on their axes in a way to be described hereinafter, and this causes the thread carriers 110 to be simultaneously reciprocated radially back and forth along radial guide slots 13 in

which fit slides 44 on which the carriers are mounted. Concentrically mounted on this disk also is a circular guide 45 projecting upwardly therefrom, and having openings 5 430 registering with the guide slots 43. On this guide are mounted a plurality of stands 46 in such a way that they can be caused to travel around on the guide. On each of these stands is a spindle or spool holder 47 carrying a spool or bobbin 48 for the upper thread ¹⁰ c. These threads are guided by needles 49 which terminate substantially on a level with the tops of the carriers 27 and have eyes at their upper ends. The number of ¹⁵ spools or bobbins are equal on the top and bottom of the disk and in the present instance twelve are shown on each side. These spools preferably are "universally" wound as shown. On the tube 21 which as stated ²⁰ rotates in a direction opposite to the rotation of the hub 22 is keyed a disk or plate 50 which carries an internal spur gear 51 meshing with a series of pinions 52 mounted on the several shafts 40. The rotation of the ²⁵ shafts on their own axes is caused by the travel of the gear or rack 51 in an obvious manner.

The way in which the upper spools are caused to travel around so as to permit the ³⁰ carriers 27 to interweave the threads of the lower spools with the threads coming from the upper spools will now be described. The disk 50 has a downwardly extending flange ³⁵ 53 at its outer edge in which are journaled a number of horizontal shafts 54 equal to the number of spools above the disk 23. On each of these shafts is a gear 55 which meshes with a gear or rack 56 carried by the lower disk. Therefore the rotation of the ⁴⁰ two disks in opposite directions will cause the shafts 54 to rotate at the same speed as the shafts 40. On each of the shafts 54 there is fixed a head 57 having a claw 58 at its outer end and having a cut-away portion 59 located between the claw and the bearing of the shaft. The stands 46 are each provided at each end with a curved groove 60 forming less than half a circle. These grooves are located on the inner sides of the stands and ⁵⁰ the stands are separated sufficiently far apart so that the two adjacent grooves are concentric and form a part of the same circle. Therefore as each shaft 54 rotates the claw 58 which is a distance from a center equal to the radius of the circle of the grooves, rotates in said circle. As these shafts 54 are bodily rotating around the center of the machine with the disk 50 their connection with the stands will cause the ⁵⁵ stands to move around at the same speed. Each stand is pushed from behind by the following claw 58 during a portion of its travel and not later than the time when this claw passes from the groove the preceding ⁶⁰ claw will enter the front groove and pull the

stand along at the same speed so that they travel around the circle at a uniform speed.

From a consideration, particularly of the plan views Figs. 2 and 3, it will be seen that as the two disks rotate in opposite directions ⁷⁰ starting for instance with each carrier 27 in the outermost position, as shown in Fig. 2, the upper series of spools will be pushed along relatively to the carriers in the direction of the outer arrow shown in Fig. 2, and at the same time the carriers will be moving inwardly. By the time the upper spools have passed from the position shown in Fig. ⁷⁵ 2 to that shown in Fig. 3 the carriers will have passed inwardly to their intermediate position as shown in Fig. 3. Then from the time that the upper spools pass from that position along to the next position similar to that shown in Fig. 2, the carriers will have passed inwardly and have been brought ⁸⁰ to the opposite sides of the spools. During the next complete half cycle of the spools the carriers will have moved outwardly a complete stroke on the other sides of the spools. In this way it will be seen that each ⁸⁵ carrier can be considered as having traveled half way around one spool and half way around the next one in the other direction, and that the threads from the lower spools will be interwoven with the threads from ⁹⁰ the upper spools. For the purpose of permitting this operation to take place the head on which the claw 58 is mounted is provided with a cut-away portion 59 as has been described. This is shown as cut-away on the ⁹⁵ arc of a circle to permit the carrier 27 to pass by it as the head rotates as shown in the position illustrated in Fig. 3. The upper spool holders are shown as provided with bottom plates 61 having such shapes that the ¹⁰⁰ carriers 27 just clear their edges during this operation. From a consideration of the two inclined strands of the thread b and c in Fig. 5, it will be clear that there is no great difference in the tension of the thread in its ¹⁰⁵ different positions, but what there is, is taken care of by the tension device. ¹¹⁰

The upper spools are provided with a stop motion constructed as follows: The needles ¹¹⁵ 49 are arranged concentrically with the upper spools. The thread is taken from each of the upper spools to the needle 49 through an eye 65 from which the thread extends upwardly over a surface 66 nearly on the level of the eye of the needle 49. The eyes 65 and surface 66 are mounted on the needles. Within each needle is a weight 68 having a hook 69 at the top passing over the thread and supported thereby. When the thread ¹²⁰ breaks this weight drops as far as a slot ¹²⁵ 70 in the needle will permit. This brings the lower end of the weight into the path of a lever 71 pivoted on the lower disk. This lever normally is held by a spring 72 in position for its tooth 73 to engage a ¹³⁰

spring-pressed bolt 74 and hold it back. When the lower end of the weight 68 engages the lever and swings it on its pivot, this withdraws the tooth 73 and allows the 5 spring to press the bolt out into position to engage the arm 33 which causes the same action as described in connection with the other stop motion.

In the form of the invention shown in the 10 rest of the figures the upper spools are not supported or guided by the lower disk 230, but are carried by elements rotating with the upper disk 500. Otherwise the two disks are the same as before and operate 15 in the same manner. In this case however the disk 230 is provided with an external gear or rack 80, shown as having the same pitch diameter as the internal gear 510, and provided with openings for the shafts 40. 20 With this gear mesh a plurality of pinions 81 on studs 811 which in turn mesh with pinions 82. The pinions 82 are mounted on shafts 83 carried by the upper disk on which shafts are fixed disks 84 and 85 to 25 rotate with these pinions. Half of these disks 84 are arranged in one plane. The others, the alternate ones 85, are arranged in a lower plane so as not to interfere with them. Each of these disks is of a general 30 circular shape, but they are provided with reentrant surfaces 86 on opposite sides, each having a curved slot 87 at the inner side thereof extending in toward the center. The shape of these surfaces is determined by 35 the motion of the parts that will be described hereinafter. The upper disks 84 are provided with a circular rib 88 projecting upwardly therefrom, and the lower disks 85 are provided with a similar 40 centric circular lower rib 89. These ribs of course are interrupted by the slots 87 which have been referred to. These disks are rotated constantly at the same speed on their own axes as the main disks travel 45 around and they are so placed that the slots 87 on two adjacent disks come into registration as the two disks rotate.

Each of the plates 610 on which the upper spools are mounted is provided with a 50 pair of plates 90-91 which are provided with segmental grooves 92 for receiving the ribs 88 and 89. These plates are so placed that the adjacent grooves in two adjacent pairs of plates are on the arc of the same 55 circle. Consequently, as the disks 84 and 85 rotate on their own axes, their ribs rotate in a circle and keep within the segmental slots in the plates 90 and 91. In this way it will be seen that the plates 610 are held 60 in a certain definite position with respect to the upper main rotating disk and are carried around with it. This disk is provided with recesses 93 in its edge from which the plates 610 are spaced laterally throughout the 65 perimeter of the same. These spaces be-

tween the edges of these recesses and plates are wide enough to receive the thread carriers 27. As the thread carrier is reciprocated, the plates travel in a circle supported by the disks 84 and 85 and when the 70 thread carrier comes back to intersect the circumferences of these rotating disks, the notches or slots 87 coincide with each other and receive the thread carriers so as to allow them to pass through these disks on the 75 way back toward the center of the main disk. After having passed back inwardly to the end of the stroke in this direction the thread carriers start outwardly again and on the way out they pass through the opposite slots or notches in the rotating disks 80 84 and 85. The particular shape of these slots and notches and timing of the gearing is not described in full herein as it will be understood that these things are designed 85 in accordance with the necessities of the case to allow of the motions above described and the drawings show a practicable form thereof. In this case as in the other, the plates 610 are designed of such 90 outline that the thread carriers always travel closely adjacent to their outer edges and, there is only a very little clearance between them, this clearance being uniform. These plates could be round or any other shape 95 but they are designed in this way to prevent operators getting their fingers caught in the machine and to prevent the deposit of waste below these surfaces.

In both forms the above described advantages are attained, and the relative motions of the thread carriers and upper spools are the same. The stop motions preferably are used on both forms.

While I have illustrated and described two 105 preferred embodiments of the invention I am aware that the invention can be embodied in many other forms within the scope of the claims. Therefore, I do not wish to be limited to all the details of construction shown and described, but

What I do claim is:—

1. In a machine of the character described, the combination of a shaft and hub mounted to rotate on the same axis, in opposite directions, a series of shafts parallel with the axis of said shaft and hub and rotatable with the hub, means for rotating said series of shafts on their axes, a series of thread carriers, means connected with said 115 shafts and rotatable about the shaft for reciprocating the thread carriers radially, a series of spools rotatable with the hub, a second series of spools, a series of shafts perpendicular to the axis of the hub rotatable with the first named shaft, and means mounted on the last named shafts for moving the second series of spools.

2. In a machine of the character described, the combination of a pair of disks 120

- rotatable in opposite directions, a series of shafts on each disk, each shaft having means thereon for receiving a rotary motion from the other disk, a series of thread carriers 5 movably mounted on one of the disks and connected with the shafts thereon to be reciprocated radially thereby, a series of spool carriers mounted to rotate with the disk on which the thread carriers are mounted, a second series of spool holders, and means on the shafts on the other disk for moving said spool holders with that disk.
3. In a machine of the character described, the combination of a pair of disks 15 rotatable in opposite directions, a circular rack on each disk, a series of shafts on each disk, each shaft having a pinion thereon meshing with the rack on the other disk, a series of thread carriers movably mounted 20 on one of the disks and connected with the shafts thereon to be reciprocated radially thereby, a series of spool carriers mounted to rotate with the disk on which the thread carriers are mounted, a second series of 25 spool holders, and means on the shafts on the other disk for moving said spool holders with that disk.
4. In a machine of the character described, the combination of a shaft and hub 30 mounted to rotate on the same axis, means for rotating said shaft and hub in opposite directions, a series of shafts parallel with the axis of said shaft and hub and rotatable with the hub, means for rotating said series 35 of shafts on their axes, a series of thread car-

riers, means connected with said shafts and rotatable about the shaft for reciprocating the thread carriers radially, a series of spools rotatable with the hub, a second series of spools, a circular rack carried by said hub, a series of shafts perpendicular to the axis of the hub rotatable with the first named shaft, gears thereon meshing with said rack, and means mounted on the last named shafts for moving the second series 40 of spools. 45

5. In a braiding machine, the combination of a rotary set of spool holders arranged in a circle, a second set of spool holders arranged in a circle concentric therewith, a rotary 50 member adapted to rotate on the same axis as the first named set of spool holders and in the opposite direction, a series of members carried by said rotary member and each rotatable on its own axis, and having means 55 for carrying the second set of spool holders around with them, a series of thread carriers movable radially, said series of members each having a passage through which a thread carrier can pass, and means for 60 bringing said passages into position to receive the thread carriers when the thread carriers approach them.

In testimony whereof I have hereunto set my hand, in the presence of two subscribing 65 witnesses.
